Charles J. Trusk,

UNITED STATES PATENT OFFICE

EDWARD E. BREWSTER, OF HOLLY, MICHIGAN.

REIN-HOLDER.

SPECIFICATION forming part of Letters Patent No. 380,676, dated April 10, 1888.

Application filed December 7, 1887. Serial No. 257,195. (No model.)

To all whom it may concern:

Be it known that I, EDWARD E. BREWSTER, of Holly, in the county of Oakland and State of Michigan, have invented new and useful 5 Improvements in Rein-Holders; and I hereby declare that the following is a full, clear, and exact description thereof, reference being had to the accompanying drawings, which form a part of this specification.

10 My invention relates to improvements in rein-holders, and is an improvement upon the invention patented to me by United States Letters Patent No. 282,609, dated August 7, 1883.

15 The object of my invention is to provide an improved apparatus to be attached to the dash-board of a vehicle, by which the driver may secure the reins from falling under the horse's feet. I attain this object by the mechanism 20 illustrated in the accompanying drawings, in which—

Figure 1 is an elevation of the entire apparatus. Fig. 2 is a section on the line xx , Fig. 1, the figure being reversed and the upper portion shown below the section. Fig. 3 is a section on the line yy , Fig. 1; and Fig. 4 is an isometric view, showing the inside of the end of the tongue of the clamp X.

Similar letters refer to similar parts throughout the several views.

In the accompanying drawings, which form a part of this specification, A represents the stationary jaw of my improved rein-holder provided with ears $a f$, between which the jaw B is pivotally secured. The jaw A is provided near its lower end with an enlargement, b, enclosing a chamber within which is seated a spring, C, and the lower end of the movable jaw B is provided with a spur, c, which enters 35 the bore of said spring and retains the same in place. The object of the spring is by its expansive force to keep the upper ends of the jaws in contact, and as these ends turn outwardly from each other they act as guides to 40 guide the reins between the two jaws, overcoming to a certain extent the resistance of the spring. The jaw A is provided with means for securing the same to the dash-board, in the figure a clamp, X, being shown for that 45 purpose, to embrace the frame of a leather dash-board. The clamp X allows the ready attachment and detachment of the device, so

that one holder will serve for several vehicles. On the inside of the clamp X are the spurs p , which are pressed into the dash-board and 55 prevent the apparatus from being accidentally displaced.

The jaw A is formed with the ear f in the position shown by the dotted lines in Fig. 2. The jaw B is then placed in position between 60 the ears $a f$, and the ear f is bent up till the lug D enters the cavity G, as shown by the full lines in Fig. 2.

K is a projection from the jaw A, which enters into a cavity, L, Fig. 3, in the jaw B. The 65 projection K slants gradually toward the upper part of the apparatus, and is perpendicular to the face of the jaw A at its lower end, as shown in Fig. 1.

The method of adjusting the reins to and 70 the operation of my device are as follows: The reins are placed between the upper ends of the jaws A and B and forced down past the projection K. The slanting face of the jaw B and the slanting ridge of the projection K allow 75 the reins to readily force the jaws A B apart on entering, while the perpendicular lower end of the projection K will prevent the reins from being accidentally disengaged. To disengage the reins, the jaws A B are spread 80 apart by the hands.

Having fully described my invention, what I wish to claim and secure by Letters Patent is—

1. A rein-holder consisting of the jaws A B, the jaw A being provided with a projection, 85 K, and the jaw B having a cavity, L, adapted to receive the projection K, substantially as shown and described.

2. In a rein-holder, as described, a latch or projection, K, slanting gradually toward the 90 top of the apparatus and forming a square shoulder at its lower end, substantially as shown and described.

3. In a rein-holder, as described, a clamp, X, provided on its inside with the spurs p , 95 substantially as and for the purpose described.

4. The combination of the jaw A, the ears $a f$, the lugs D H, with the jaw B, provided with the cavities E G, substantially as described.

EDWARD E. BREWSTER.
